4 Claims

This application is a continuation-in-part of our pending application Ser. No. 19,111, filed Mar. 31, 1960 and now U.S. Patent No. 3,354,216.

This invention relates to highly fluorinated compounds of carbon and nitrogen and particularly to certain very highly fluorinated oxidizing agents containing fluorine, nitrogen and carbon, and the process for the preparation thereof.

It is well known that fluorine is the most electronegative element and therefore is an oxidizing agent with very high potential. However, fluorine is a very low boiling and highly corrosive gas requiring rather special techniques in its manipulations, which limits the extent to which its high oxidizing potential could otherwise be utilized for use where high output is required. Among such possible uses are a number of industrial processes where high oxidizing potential can extend the range of application, increase rate of output and the like. Many industrial requirements have heretofore been met in a more or less satisfactory way using less powerful and more readily handled oxidizing agents. Bleaching of wood pulp, fabrics, flour and such materials may be mentioned among such uses. However, more active oxidizing agents would be advantageous in such industrial uses if readily handled, permitting shorter process time, use of lower concentration, etc. Another field in which very high oxidation potentials are particularly desirable is in the field of reaction-type propellants where extreme releases of energy are necessary to achieve high specific impulses. For such purposes the availability of relatively safely handled material possessing even a substantial fraction of the oxidizing capacity of fluorine but still at a high potential would be very desirable in formulating solid propellants, or for use as oxidizers in liquid propellant systems.

It is known that the oxidizing potential of fluorine is retained to a considerable extent in $=\text{NF}_2$ and $=\text{NF}$ radicals but methods of synthesis of compounds containing such radicals are very severely limited and the introduction of a plurality of such radicals into a molecule has heretofore been extremely difficult.

It is an object of this invention to provide fluorine-containing compositions having substantial oxidizing capacity. A further object is to provide highly fluorinated derivatives of guanidine containing fluorine in oxidizing configurations. A still further object is to provide oxidants having high oxidizing capacity at a high potential. Another object of the invention is to provide a process for producing the compositions of the invention. Other objects will become evident hereinafter.

In accordance with the above and other objects of this invention, it has now been found that compositions containing a plurality of $=\text{NF}_2$ and $=\text{NF}$ groups are formed by direct fluorination of compounds containing at least one carbon atom bonded to three nitrogen atoms. One type of these compounds is believed to be represented by the formula:

2

wherein n is a large number from about 50 to 1000 or greater. These compounds are described by A. E. A. Werner in the Scientific Proceedings of the Royal Dublin Society, volume 24, page 199 ff. for 1947 and the above structure is suggested as well as the less probable isomeric structure represented by the formula:

No attempt is there made to name these polymeric compounds. It will be noted that the recurring units of the first structure are carbonylguanidylene radicals which are divalent. The termination of the chains is probably as shown. It will be understood that we are not limited to the structures postulated in using these names but refer specifically to substances formed by interaction of guanidine with either urea or urethane. It has now been found that a significant amount, up to about equal parts of ammeline is formed by the Werner process for preparing polycarbonylguanidylene and is present in the reaction product since it is not separated by Werner's purification procedures. As pointed out hereinbelow, the products of the invention are also produced by the fluorination of ammeline alone, as well as by the fluorination of the mixture produced by the Werner process.

Other compounds useful for the purposes of the invention are the acyclic compounds guanidine hydrochloride, dicyanamidazole, biguanide, triguanide and the hydrofluorides thereof; the monocyclic compounds melamine, ammeline and ammelide and the polycyclic compound potassium cyamelurate. It will be seen that all of these compounds include in their structure the characteristic structural grouping of at least one carbon atom attached to three nitrogen atoms.

It has been disclosed heretofore that guanidine itself, as well as urea, hydrazine, biuret and the like compounds when subjected to direct fluorination either are extensively cleaved and produce substantially only very low-boiling products or are very incompletely fluorinated to produce solids having no appreciable oxidizing capacity. However, we have found that the highly useful compounds of this invention can be obtained by the techniques described herein.

The fluorination of the starting materials set forth above produces highly fluorinated, shock-sensitive oxidant compositions which contain substantially only carbon, nitrogen and fluorine in acyclic configuration, containing at least two fluorinated nitrogen atoms, and having a ratio of nitrogen:carbon atoms ranging from 1:1 to 3:1; and characterized by containing more than about 25% of fluorine and having oxidizing capacity equal to at least about 5 to 50 milliequivalents of iodine per gram. These compounds have the formula:

wherein R is a member of the group consisting of $=\text{NF}$, $=\text{NF}_2$, $=\text{NCF}_3$, $=\text{NCF}_2\text{NF}_2$, $=\text{NCF}=\text{NF}$, $=\text{NCF}(\text{NF}_2)_2$,

$=\text{N}-\text{CF}_3$, $=\text{NCF}_2\text{NF}_2$, $=\text{NCF}=\text{NF}$ and $=\text{NCF}(\text{NF}_2)_2$ radicals; Y is a linking radical of the group consisting of

and $=C=$ radicals; Z is a member of the group consisting of $-F$, $-CF_2NF_2$, $-CF=NF$,

and $-CF(NF_2)_2$ radicals; n is an integer of the group consisting of zero and one; and R is a divalent radical

only when Y is a linking radical of the group consisting of

and $=C=$, and n is zero when Y is $=C=$.

Exemplary compounds of this type are set forth in the following table:

Name	Structure	F-N bonds	C-F bonds
Bis(disfluoroamino)disfluoromethane		4	2
Tris(disfluoroamino)fluoromethane		6	1
Perfluoroguanidine		5	0
Perfluoroformamidine		3	1
Disfluorocarbodiimide		2	0
Bis[bis(disfluoroamino)fluoromethyl]fluoroamine		9	2
N-(disfluoroaminodisfluoromethyl)-perfluoroformamidine		4	3
[Bis(disfluoroamino)fluoromethyl]-trifluoromethylfluoramine		5	4
N-[Bis(disfluoroamino)fluoromethyl]-perfluoroformamidine		6	2
N-fluoro-N'-(disfluoroaminodisfluoromethyl)-carbodiimide		3	2
Bis[bis(disfluoroamino)fluoromethyl]fluoroamino-fluorodisfluoromethane		12	3
Disfluoroaminodisfluoromethyl[bis(disfluoroamino)fluoromethyl]fluoroamino		7	3
N,N'-bis(perfluoroformimidyl)-N,N'-trifluoroguanidine		5	2
N-(perfluoroformimidyl)-N'-(disfluoroaminodisfluoromethyl)-N,N',N"-trifluoroguanidine		6	3
Perfluorobiguanide		7	0
Perfluorotriguanide		9	0
N,N'-bis(perfluoroformimidyl)-carbodiimide		2	2

Name	Structure	F—N bonds	C—F bonds
N-(difluoroaminodifluoromethyl)-N',N'-difluorofluoroformamidine.	$ \begin{array}{c} \text{F} \\ \\ \text{F}_2\text{N}—\text{C}—\text{N}=\text{C}—\text{NF}_2 \\ \quad \\ \text{F} \quad \text{F} \end{array} $	4	3

It will be noted that in the third, fourth, fifteenth and sixteenth formulas the carbon-nitrogen double bond is intact although empirically the compound is named as perfluorinated. The significance of the content of fluorine to nitrogen bonds is that such bonds possess energy and are powerful oxidants. It was not heretofore believed that direct fluorination reactions resulted in useful and stable products with high contents of nitrogen to fluorine bonds.

Thus, it is found that direct fluorination using elemental fluorine replaces substantially all of the hydrogen atoms contained in these source materials by fluorine atoms, whether these compounds are present undiluted or as a suspension in a suitable liquid inert to fluorine. It appears from what can be determined from the stoichiometry of the reaction and the analytical values obtained on the products that the reaction not only replaces substantially all of the hydrogen atoms by fluorine atoms but that in addition greater or lesser amounts of fluorine combine with the source materials, e.g. poly(carbonylguanidylene), by addition to the carbon-nitrogen double bonds which are present. Addition of fluorine also causes some cleavage of the C—N skeletal chain of the polymeric and cyclic substances. The resultant products, which vary over certain ranges of fluorine content, contain a number of compounds which can be isolated by the methods described herein. There is reason to believe that not all of the double bonds present add fluorine and fluorinolysis would be expected to result in complete decomposition of the source materials to produce CF_4 , COF_2 , and HF . Surprisingly, the reaction stops well short of complete degradation to produce white to yellowish, liquid and amorphous materials, which may be non-crystalline to sticky solids, greases, or mobile liquids which may be low-boiling in which the fluorine content on analysis may vary from about 25 percent to about 75 percent by weight and the oxidizing capacity determined as described hereinbelow is from about 5 to 50 or more milliequivalents of iodine per gram. Oxidizing capacity is determined using excess potassium iodide in aqueous acetonitrile or acetic acid followed by titration with standard solutions of sodium thiosulfate. The products have vapor pressures up to about 100 mm. of Hg at -78°C . to less than 50 mm. of Hg at 25°C , and are considered to comprise both volatile and nonvolatile substances. The low vapor pressure amorphous compositions of the invention are shock-sensitive, but are usually not so sensitive that they cannot be handled conveniently.

There is a wide range of sensitivity among compounds which are sensitive to shock or impact. Many such compounds, although sensitive, can be used safely; commercial explosives fall in this class. A widely-used method of evaluating the degree of sensitivity consists of dropping a weight (frequently a two kilogram weight is employed) onto a small sample of the compound and determining the height of drop at which detonation occurs. The product of the weight used and height of drop, expressed in kg. cm., is then a measure of the sensitivity and this product is greater for the less sensitive materials.

The materials herein described have sensitivities, expressed as kg. cm., which place them outside the range of the most sensitive materials. They can accordingly be manipulated using suitable precautions, and thus they are different from many known materials having high oxidative capacity which cannot safely be manipulated. It is, of course, only normally prudent to exercise considerable care under all circumstances since, when detonated, materials of such high energy content produce very violent explosions and in fact are so powerful as oxidizing agents that they can ignite many common organic substances. In no case should quantities over about 10 milligrams be detonated for testing.

The amorphous compositions of the invention are thus seen to be amorphous, shock-sensitive compositions which contain carbon, nitrogen and fluorine, and which have an oxidizing capacity of from about 5 to 50 or more milliequivalents of iodine per gram. They appear to consist of mixtures of similar compounds with somewhat different physical properties, which are separated from each other with difficulty. They contain substantially no residual hydrogen in the molecule, and, when they are solids, are insoluble in the common organic solvents, but can be dispersed in a variety of inert solvents and are generally soluble to some extent in fluorocarbon solvents. The liquid products are soluble in such solvents as methylene chloride, fluorotrichloromethane and the like. The solid materials do not melt, but decompose on heating; certain of the liquids may be distilled with great caution under highly reduced pressure; others may be distilled readily at atmospheric pressure. When mixed with substances which can be oxidized, such as an organic polymer, and ignited as by means of a squib, they burn with intense heat and the formation of large volumes of gases. When treated with water, or exposed to moisture, these fluorinated compounds may hydrolyze to a greater or less extent with a lowering or loss of their oxidizing power.

The more volatile products, which are often normally gaseous, are relatively shock insensitive in the pure state and consist of carbon, nitrogen and fluorine and have oxidizing capacities of from about 5 to upwards of 50 milliequivalents of iodine per gram. They are somewhat separable by distillation and more completely by vapor phase chromatography employing a fluorochemical stationary phase as more fully described hereinafter. They are generally relatively soluble (even when gases) in fluorocarbon solvents such as perfluoro "octane" and higher boiling products of the reaction and are much less soluble in hydrocarbons. Their reactivity is variable. Those which possess a $\text{C}=\text{N}$ bond are readily hydrolyzed by dilute (e.g. 5-10%) aqueous alkali at ordinary temperatures whereas the saturated compounds are relatively stable to this reagent under the same conditions.

Broadly speaking, the process of the invention is carried out by treating the carbonylguanidylene polymers and other source materials with elemental fluorine. For best results, the starting material should be substantially anhydrous, to avoid destruction of the $=\text{NF}$ or $—\text{NF}_2$

groups after their formation. The process can be carried out at a temperature in the range of about -100 to $+40^{\circ}$ C. or even somewhat higher. Reaction takes place very slowly at -100° C. and is markedly increased by raising the temperature to -75° C. or higher. The fluorine is conveniently introduced under slight positive pressure, or if closed vessels are used, by employing diluents and proper precautions, pressures up to 100 p.s.i. can be used. Preferably, the fluorine is diluted with nitrogen or other inert gas such as argon or helium, or a Freon, such as dichlorodifluoromethane and the like, to give about 0.1 to 60 percent of fluorine in the gas stream. Too high a concentration is indicated by burning of the starting materials and this can be avoided by reduction of the fluorine concentration and/or lowering the reaction temperatures, however, undiluted fluorine can be used, using great caution and slow addition when working with solid, finely powdered undiluted reactants. Residual fluorine should always be flushed out of the reactants and the apparatus, using dry nitrogen or the like, to avoid unpleasant and toxic exposure to fluorine as well as untoward effects owing to the strong oxidizing power of this substance. The apparatus used is preferably constructed from monel metal or copper. The solid, in finely divided form, is placed in a suitable container, such as a boat, which may be of stainless steel or copper or spread on a sheet or plate, and is then contacted with fluorine for a period ranging from about 10 minutes to about 6 hours. Longer times are usually used with more highly diluted fluorine and for large samples. Generally speaking, once the process has gone to completion, no further fluorine reacts, so that continuation of the flow of fluorine is not deleterious; but excessive exposure to fluorine, of the order of 10 hours or more when highly concentrated fluorine is used, should be avoided to suppress the possibility of extensive fluorinolysis. Preferably, the reaction mixture is maintained at a temperature in the range of about -20 to $+25^{\circ}$ C. and the fluorination process is continued for about 5 hours or longer for larger samples. The time depends on the fluorine flow rate as well as sample size. When convenient, lower temperatures can be used and it is preferred to use temperatures not in excess of about 25° C. If desired, an inert liquid suspending medium can be used to suspend the finely divided reactant, and the fluorine gas with or without a diluent gas is then bubbled through the suspension. Thus, for example, fluorine-inert liquids such as perfluorinated hydrocarbons, e.g. perfluoroctanes, perfluorohexanes, and the like; perfluorocyclohexanes; perfluorinated cyclic ethers such as perfluorobutylfuran; perfluorinated tertiary amines such as triperfluoro-n-butylamine; and the like. Commercially obtainable fluorocarbons may contain an amount of material which is not inert toward fluorine, and in such cases, fluorine gas is passed through the selected fluorocarbon liquid for a time in small amounts just sufficient to render it substantially completely inert toward fluorine. When an inert liquid diluent is employed in the process of the invention, the hyperfluorinated reaction product generally dissolves in the diluent. The reactant may also be mixed with a finely divided solid material which is inert to fluorine under the conditions of fluorination; such materials include sodium fluoride, calcium fluoride and graphite. The fluorine gas is then passed over or through the solid mixture.

In the procedure where no solvent is used, the product of the process is recovered for use by removal of the excess of fluorine gas and separation from any highly volatile fluorinated cleavage products such as CF_4 , NF_3 , etc. which may be present. Where solvent is employed, any insoluble material is removed by filtration and the product is recovered by evaporation of the solvent, preferably under reduced pressure.

The following examples will more specifically illustrate the fluorinated oxidant compounds of the invention and the process for their preparation.

Example 1

This example illustrates the process of the invention in which no diluent is employed. This process is referred to as static bed fluorination.

- 5 The reaction product of guanidine and urethane is prepared as described by A. E. A. Werner in Scientific Proceedings of the Royal Dublin Society, vol. 24, p. 199 (1947) and has an inherent viscosity of 0.162 in trifluoroacetic acid. It has now been found to be a mixture of about equal parts of poly(carbonylguanidylene) and ameline.
- 15 In a stainless steel boat is placed a sample of 205 mgm. of the above dry mixture and the boat is placed in a 1 inch by 14 inch nickel tube having a polytetrafluoroethylene rupture disc at one end and arranged by means of a side arm, so that gases can be introduced at one end and removed at the other. A stream of dry prepurified nitrogen is forced through the tube containing the sample at about 130 ml. per minute to displace air since fluorine 20 subsequently introduced may produce explosives with oxygen. Fluorine (commercially available, 95 percent pure) is introduced into the nitrogen stream (using monel metal fittings) to give a concentration of 8.9 percent fluorine by volume and the stream of nitrogen and fluorine 25 is passed over the mixture at about 20° C. for 3.66 hours. The volatile and entrained fluorination products are removed at the far end of the tube, passed through sodium fluoride in an iron tube heated to about 90° to 105° C. (to remove hydrogen fluoride) and any residual materials 30 are condensed in a borosilicate glass trap cooled in a liquid air bath. At the end of 3.66 hours the flow of fluoride is stopped and that of nitrogen continued for about 30 minutes to flush through residual amounts of fluorine. The stainless steel boat contains a yellow amorphous solid. 35 Decomposition by the procedure reported by Senkowski, Wolliski and Shafer in Analytical Chemistry, vol. 31, pp. 1574-1576 (1959) followed by titration with standard thorium nitrate solution using sodium Alizarin Red S as indicator shows 34.7 percent by weight of fluorine. Reaction of a sample with excess potassium iodide in acetonitrile followed by titration using standard iodometric 40 procedures shows that the amorphous yellow hyperfluorinated material has an oxidizing capacity of 14.1 milliequivalents (meq.) of iodine per gram. For this product the impact sensitivity was less than 100 kg. cm. The minimum value is not usually determined. The fluid and liquid products formed in this reaction and entrained by the gas stream is not conveniently recovered on this scale although a trace of liquid is found in the liquid-air trap. 45
- 50 In other runs using 219 and 314 mgm. amounts of material with from 5.7 to 3.6 percent by volume of fluorine and for 1.87 and 4.58 hours at 22° and -70° C., all respectively, other mixtures of solid products are obtained having oxidizing capacities of 14.9 and 7.8 meq. iodine per gram respectively.

Example 2

- 55 The procedure of Example 1 is repeated employing 1101 mgm. of the same starting material. The fluorination vessel is a copper U-tube maintained at about -70° C. by means of solid carbon dioxide through which a stream of 8.57 percent fluorine concentration is passed for 5 hours (total of 0.12 mole of F_2) at the end of which time the reactor is allowed to warm up to room temperatures and the nitrogen stream is continued for 3 to 5 hours to flush through fluorine and entrain as much as possible of the more volatile products. The gases pass through a sodium fluoride scrubber as above. On this larger scale an appreciable amount of material is collected in the liquid air trap as well as a substantial amount of yellowish solid remaining in the reactor. The solid material contains 32.4 percent fluorine by weight and has an oxidizing potential of 7.4 meq. iodine per gram.
- 60 The liquid in the trap designated as A is separated into fractions by connecting the trap (kept cold in liquid air) 65

70

to a line passing serially through two receivers herein designated B and C. The first receiver, B, is cooled to -78° C. by a carbon dioxide-trichloroethylene bath and the second receiver, C, is cooled in liquid air. The liquid air bath surrounding the original trap, A, is removed and the contents permitted to vaporize as the temperatures gradually rise to ambient temperature. A liquid residue remains in the original trap. The less volatile portion of the vapors is condensed in receiver B, the more volatile material in receiver C. The product in C contains fragments such as CF_4 , NF_3 , and CO_2 and is usually discarded. Both compositions in B and the original trap, A, are mixtures, part of the more volatile components being retained in trap A as a result of solubility in the less volatile constituents of that composition. The product distribution in trap A and B can vary considerably by varying the time in which trap A is maintained at the ambient room temperature. On a run using twice the amount of starting material, the residue remaining in trap A was found to contain a liquid residue not evaporated at 46 mm. Hg and 25° C. which was found to be sensitive to shock, heat and even to the light contact between a glass pipette containing some of the material and the walls of the container. The contents of receiver B is analyzed by vapor phase chromatography using a polytrifluoroethylene oil as the continuous phase, nuclear magnetic resonance and infrared absorption spectroscopy and is found to consist of a mixture of about 75 percent of a mixture of low molecular weight cleavage products, e.g. CF_3NF_2 , $(\text{CF}_3)_2\text{NF}$, COF_2 , NF_3 and SiF_4 , and about 25 percent of a mixture of other compounds, including appreciable amounts of $\text{CF}_2(\text{NF}_2)_2$ and a small amount of $\text{CF}(\text{NF}_2)_3$. By the same method, the contents of trap A is found to consist of about 25 percent of a mixture of low molecular weight cleavage products, e.g. trifluoromethyl-difluoramine etc. and about 75 percent of other compounds including as the major components, $\text{CF}_2(\text{NF}_2)_2$ and $\text{CF}(\text{NF}_2)_3$. In each case, further separation into fractions can be accomplished by vapor phase chromatography and the compounds present in significant amount can be isolated. Compounds which were initially isolated include bis(difluoroamino) difluoromethane ($\text{CF}_2(\text{NF}_2)_2$) and tris(difluoroamino) fluoromethane ($\text{CF}(\text{NF}_2)_3$).

The contents of tray B above is further characterized by the nuclear magnetic resonance shielding values (employing CFCl_3 as internal standard as described by Filipovich et al., Journal of Physical Chemistry, vol. 63, pp. 761-762 (1959); the ϕ^* values defined by these authors are here given simply as ϕ values) and shows the following important peaks (all such values are approximate to about 1%):

- -23.4ϕ —F or NF_2 in $\text{CF}(\text{NF}_2)_3$
- -19.7ϕ —F of NF_2 in $\text{CF}_2(\text{NF}_2)_2$
- 0.0ϕ — CFCl_3 reference
- $+71.1\phi$ —Doublet: F of CF_3 in $(\text{CF}_3)_2\text{NF}$
- $+84.4\phi$ —F of CF_3 in CF_3NF_2
- $+100\phi$ — CFCl_3 reference
- $+112.8\phi$ —F of CF_2 in $\text{CF}_2(\text{NF}_2)_2$
- $+138.7\phi$ —F of CF in $\text{CF}(\text{NF}_2)_3$
- $+163.8\phi$ —F in SiF_4

The intensities of the peaks due to $\text{CF}_2(\text{NF}_2)_2$ and $\text{CF}(\text{NF}_2)_3$ are in approximately the theoretical ratios as hereinafter described.

The residue in trap A is evidently less volatile. The infrared absorption spectrum shows a high ratio of N—F bonds in the 10-11 micron region to C—F bonds (7.5 to 8.5 micron region) and some unsaturation (4.3 to 6.4 micron region).

Nuclear magnetic resonance shielding values permit the further characterization of this mixture from the following values:

- -47.2ϕ , -42.4ϕ —peaks of about equal area due to F of $=\text{NF}_2$ in perfluoroguanidine
- -24.3ϕ —F of NF_2 in $\text{CF}(\text{NF}_2)_3$

- -20.0ϕ —F of NF_2 in $\text{CF}_2(\text{NF}_2)_2$
- -19.0ϕ —and shoulder at less negative value due to F of $=\text{NF}$ in perfluoroguanidine
- $+67\phi$ —(and $+69$) two very weak unrecognized peaks of about equal area probably due to F in CF_3 groups
- $+71.2\phi$ —doublet: F of CF_3 in $(\text{CF}_3)_2\text{NF}$
- $+84.2\phi$ —F of CF_2 in CF_3NF_2
- $+85.7\phi$ —(and shoulder to higher values) unassigned C—F and N—F peaks
- $+100\phi$ — CFCl_3 reference
- $+112.9\phi$ —F of CF_2 in $\text{CF}_2(\text{NF}_2)_2$
- $+138.4\phi$ —F of CF in $\text{CF}(\text{NF}_2)_3$

The peaks at -24.3 and -19.0 are rather broad and presumably obscure N—F peaks which are correlated with the small amounts of material responsible for the unassigned peaks at about $+67$ and $+85.7$. Vapor phase chromatography shows the presence of about 1 percent of at least one more compound than can be recognized unequivocally and there is a suggestion in the nuclear magnetic resonance curve of several very small peaks which are scarcely distinguishable from background "noise."

In order to prepare $\text{CF}_2(\text{NF}_2)_2$ and $\text{CF}(\text{NF}_2)_3$ in substantially pure form the contents of trap A and receiver B from a series of several runs are pooled and fractionated to remove materials boiling below about -40° C. which includes virtually all the low molecular weight cleavage products, e.g. CF_3NF_2 , NF_3 and CF_4 . The residue can then be further rectified to provide a fraction having a vapor pressure at -75° of equal to or less than 40 mm. and a vapor pressure at $+25^{\circ}$ of greater than 25 mm. This mixture, having an estimated boiling range of -30° to $+25^{\circ}$, consists largely of $\text{CF}_2(\text{NF}_2)_2$, $\text{CF}(\text{NF}_2)_3$ and other compounds of high NF content. It is found that $\text{CF}_2(\text{NF}_2)_2$ and $\text{CF}(\text{NF}_2)_3$ are accompanied by a considerable number of fluorinated compounds in varying amounts.

In this manner a sample is subjected to vapor phase chromatography employing the above-mentioned fluorocchemical stationary phase to concentrate the substances (including $\text{CF}_2(\text{NF}_2)_2$ and $\text{CF}(\text{NF}_2)_3$) having high N—F bond content and a single fraction is obtained corresponding to $\text{CF}(\text{NF}_2)_3$. This material is found by infrared spectral analysis to contain an unsaturated component which had only NF and no CF absorption and which is confirmed by nuclear magnetic resonance shielding values to be prefluoroguanidine. The peaks are:

- -47.5ϕ , -42.5ϕ —Peaks of about equal intensity due to F in the NF_2 groups of perfluoroguanidine
- -23.1ϕ —Peak due to F of NF_2 groups $\text{CF}(\text{NF}_2)_3$
- -19ϕ —Shoulder on -23.1 peak due to F of the $=\text{NF}$ group in perfluoroguanidine of much lower intensity than the above two peaks.
- $+138\phi$ —F in CF group of $\text{CF}(\text{NF}_2)_3$

Planimetrically the areas of the four peaks (the shoulder at -19ϕ being included in the -23ϕ peak) are respectively about 0.5:0.5:6.1:1. It is seen that the shoulder contributes only a small fraction, ca. 0.2, to the area of the larger peak and that the substance in question must be perfluoroguanidine since there are no unassigned peaks even of very low intensity.

As a result of the above vapor phase chromatography a fraction containing a considerable amount of $\text{CF}_2(\text{NF}_2)_2$ is also obtained. The infrared absorption spectrum shows weak intensity peaks at 4.38, 4.58 and 5.85 microns which indicate probable unsaturation. Nuclear magnetic resonance shows the presence of a compound, perfluoroformamidine, having three types of fluorine bonds (-42.3ϕ , $+83.5\phi$ and very weak at about $+21\phi$) as well as some other compounds.

In order to separate $\text{CF}_2(\text{NF}_2)_2$ and $\text{CF}(\text{NF}_2)_3$ in pure condition with the least effort, although at the expense of some of these other substances, the gases containing $\text{CF}_2(\text{NF}_2)_2$ and $\text{CF}(\text{NF}_2)_3$ are scrubbed with aqueous

sodium hydroxide (5 to 10% by weight) at about 25° C. and dried over CaSO_4 before vapor phase chromatography. This results in destruction of the more reactive concomitants, particularly perfluoroformamidine and perfluoroguanidine, and simplifies the separation. Substantially the same result is achieved by exposing the gases to ultraviolet irradiation of wave lengths above about 2500 Å. At shorter wave lengths $\text{CF}_2(\text{NF}_2)_2$ and $\text{CF}(\text{NF}_2)_3$ also show a tendency to decompose.

For preparative purposes a Beckman Megachrom 12 foot GLC column is packed with tetrameric polytrifluorochloroethylene absorbed on specially prepared diatomaceous earth. The column is held at 25° C., the block at 90° C. The sample is introduced and moved in a stream of helium under a pressure of 6 lbs. per square inch at the inlet and 1 lb. per square inch at the outlet. The samples (previously scrubbed with aqueous sodium hydroxide) are stored in and injected into the system from a barricaded steel cylinder. The compound, $\text{CF}_2(\text{NF}_2)_2$, is eluted in 9.5 minutes (peak) and $\text{CF}(\text{NF}_2)_3$ in 24.5 minutes (peak).

Bis(difluoroamino)difluoromethane ($\text{CF}_2(\text{NF}_2)_2$) is colorless both as a liquid and as a gas and is found to be relatively shock insensitive. Its vapor pressure in mm. (P), when T is the absolute temperature in ° K., is approximately expressed by the equation:

$$\log P = 7.653 - \frac{1149}{T}$$

The boiling point at atmospheric pressure is thus about -32° C. and the heat of vaporization is about 5.3 kcal./mole. Its density at 25° C. was found to be 1.901 g./cc. (under pressure). The infrared absorption spectrogram shows a strong double peak at 7.7 to 8.0 microns corresponding to the C—F bonds and two strong peaks at about 10.4 and 11.0 microns corresponding to the $-\text{NF}_2$ groups.

Analysis.—Calculated for CF_2N_2 : 7.8% C; 74.0% F; 18.2% N; mol. wt. 154. Found: 8.1% C; 73.1% F; 17.9% N; mol. wt. 150.

Bis(difluoroamino)difluoromethane possesses nuclear magnetic resonance shielding values (using chlorotrifluoromethane as internal reference) at -19.0ϕ (corresponding to the four equivalent nitrogen to fluorine bonds) and at $+112.9\phi$ (corresponding to the two equivalent carbon to fluorine bonds). It has long been known that nuclear magnetic resonance (often abbreviated as n.m.r.) can serve as a means for group analysis, i.e. functional groups involving hydrogen, as well as for fluorine. An example is provided by Gutowsky, Analytical Applications of Nuclear Magnetic Resonance in Berl, Physical Methods of Chemical Analysis, volume 3, pp. 303-381, Academic Press, N.Y. (1956). While the errors in determinations of the intensities may be fairly high (for a discussion see, R. B. Williams, Annals of the New York Academy of Sciences, vol. 7, pages 890-899 (1958)), a large part of the error is smoothed over in relatively simple molecules such as low boiling liquids and normally gaseous materials of the invention where the relationships of the intensities must be as ratios of small whole numbers and where furthermore only a limited number of types of groups are involved. For $\text{CF}_2(\text{NF}_2)_2$ it is found that the ratio of the intensities of the peaks at -19.0ϕ and $+112.9\phi$, respectively, are close to 2:1. This is in agreement with the required relationship of intensities of 4:2 based upon the presence in the molecule for four nitrogen to fluorine and two carbon to fluorine bonds. The intensities of the respective peaks are readily measured on the plotted curves as the integrals of the peak and may be determined by any of the usual methods for integration, e.g. by planimetry, graphically or by weighing of the cut-out curve. It is equally possible to proceed from the n.m.r. data to determine the structure. The presence of only two types of fluorine bonds indicates a simple structure. The ratio of

2:1 of F—N to F—C bonds and the fact that each N requires two fluorine atoms also leads to the structure.

Tris(difluoroamino)fluoromethane ($\text{CF}(\text{NF}_2)_3$) is colorless both as a liquid and as a gas and is found to be relatively shock-insensitive. Impact sensitivity is deter-

10 mined at 50% firings at 50 kg. cm. using an Olin-Mathieson Liquid Test Apparatus based on adiabatic liquid compression and handling samples (initially cooled with solid carbon dioxide) under anhydrous conditions. It is stable in solution in CCl_4 at 200° C. for at least 15 hours and 15 as a gas can be stored in borosilicate glass vessels for months without evidence of decomposition. Its vapor pressure in mm. (P), when T is the absolute temperature in ° K., is approximately expressed by the equation

$$20 \log P = 7.958 - \frac{1414}{T}$$

from which the boiling point at atmospheric pressure is calculated to be about +5° C. and the heat of vaporization to be about 6.5 kcal./mole. The density of the liquid 25 at -75° C. is about 1.9 g./cc. The infrared absorption spectrogram shows a strong sharp peak at 7.8 microns corresponding to the CF group and a strong broad complex series of three major peaks between 10 and 11 microns corresponding to the $-\text{NF}_2$ groups.

30 *Analysis.*—Calculated for CF_7N_3 : 6.4% C; 71.1% F; 22.5% N; mol. wt. 187. Found: 6.5% C; 71.8% F; 22.1% N; mol. wt. 183.

The oxidizing capacity was found to be 46.3 meq. of iodine per gram.

35 Nuclear magnetic resonance shielding values (using chlorotrifluoromethane as the internal standard) at -23.8ϕ (relative intensity of 6+) (corresponding to F—N bond) and at $+138.7\phi$ (corresponding to F—C bonds) show the presence of 6 F—N bonds for each F—C bond. This is only possible in the structure

40 and is the highest such ratio known for any organic compound.

Example 3

The vapor phase chromatographic separation described 50 in Example 2 is repeated employing the same trap contents from a similar run but without treatment thereof with aqueous sodium hydroxide. The concomitant perfluoroformamidine is eluted immediately after $\text{CF}_2(\text{NF}_2)_2$ and perfluoroguanidine with $\text{CF}(\text{NF}_2)_3$. Both substances 55 are low boiling liquids (gases at normal temperatures).

Perfluoroformamidine is found to have infrared spectral absorption peaks as follows (wavelengths in microns).

60 Weak absorption—4.60; 14.47: unassigned
Moderate absorption—8.62 (C—F), 9.55 (unassigned);
10.14 (N—F) 13.21, 13.90 (unassigned)
Strong absorption—5.86 (C=N), 7.75 (C—F)
Very strong absorption—10.61; 11.23 (both N—F)

65 Three nuclear magnetic resonance shielding values are observed corresponding to the three types of bound fluorine atoms:

70	Position	Structural Assignment	Relative Intensity
	-42.2 ϕ	$-\text{NF}_2$	2.0
	+21.2 ϕ	$=\text{N}-\text{F}$	1.0
	+83.0 ϕ	$\equiv\text{C}-\text{F}$	0.8

These are thus in the simple ratio of 2:1:1 and since each 75 F_2N group includes two F's of the first type it follows that

the structure includes one each of NF_2 , $=\text{N}-\text{F}$ and $\text{C}-\text{F}$ and is unambiguously

The n.m.r. structure proof is verified by elemental analyses.

Calculated for CF_4N_2 : 10.3% C; 24.2% N; 65.5% F. Found: 10.4% C; 24.0% N; 64.5% F.

Associated with $\text{CF}(\text{NF}_2)_3$ is a compound which can be recovered by rechromatography employing a liquid or rubbery copolymer of trifluoromethylsulfide and tetrafluoroethylene or other high boiling fluorochemical liquid as the stationary phases. One suitable fluorochemical is the residue of polymeric material boiling at about 100° to 140° at 1 mm. of Hg pressure formed during the electrochemical fluorination of tributylamine. Perfluoroguanidine is found to exhibit infra red absorption as follows:

Very weak—6.13 (nearly symmetrical $\text{C}=\text{N}$)

Weak—9.46 ($\text{N}-\text{F}$), 12.78 (unassigned)

Moderate—14.19 (unassigned)

Strong—10.10, 10.66 (both $\text{N}-\text{F}$)

Very strong—11.03 ($\text{N}-\text{F}$)

Three nuclear magnetic resonance shielding values corresponding to the different types of fluorine bonds are observed:

Position	Structural Assignment	Relative Intensity
-20ϕ	$=\text{N}-\text{F}$	1
-42ϕ	$-\text{NF}_2$	2
-47ϕ	$-\text{NF}_2$	2

The different F_2N groups are ascribed to the two NF_2 groups being somewhat unlike. It is apparent from these data that the structure is unequivocally

Example 4

This example illustrates the process of the invention in which the poly(carbonylguanidylene)-ammeline mixture is suspended in a fluorine-inert liquid for fluorination.

A suspension of 750 mgm. of the mixture in 50 ml. of perfluoro "octane" (a mixture of perfluorinated C_8 isomers) is placed in a monel metal flask having standard taper connections and fitted with an inlet for gas from a mixing manifold, a thermocouple and a vent line passing to a monel metal condenser. All leads through which fluorine gas is to pass are constructed of monel metal and a polytrifluoromethylchloroethylene rotameter tube with a monel metal ball is employed to gauge the rate of flow. Nitrogen is passed through the suspension for a few minutes to flush oxygen from the system and fluorine is gradually introduced into the stream and the nitrogen concentration decreased during 0.5 hour until undiluted fluorine is passing through the suspension. This procedure is reversed after about 2.6 hours toward the end of the reaction to decrease the concentration of fluorine to zero so that a total of about 22.5 g. of fluorine has been passed through the suspension. The temperature is maintained at about 28° to 30° C. After flushing with nitrogen, the suspension is filtered through a sintered glass filter and a small amount of partially fluorinated guanidine-urethane polymer is recovered. The filtrate is evaporated carefully in vacuo to give an amorphous grease-like hyperfluorinated product which, on analysis, is found to contain 48.5 percent F. and to have an oxidizing capacity of 19.7 meq. of iodine per gram. The impact sensitivity is less than 70 kg. cm. It is apparent that some of the more volatile products such as those described in Example 2 above are entrained and codistilled during evaporation of the per-

fluoro "octane" solvent since after distillation this recovered solvent is found to possess an oxidizing capacity not found before use. The presence of such products is also demonstrable by vapor phase chromatography.

When the above procedure is repeated at a reaction temperature of about -47° to -35° C. and using larger amounts of fluorine at lower concentration for a longer time it is found that a greater amount of incompletely fluorinated insoluble solid is recovered and the amorphous greasy hyperfluorinated product is more shock-sensitive with somewhat higher oxidizing capacity.

Example 5

A poly(carbonylguanidylene)-ammeline mixture is prepared by heating 18 g. of guanidine carbonate and 12 g. of urea (equimolar amounts) at 110° to 130° C. for 2.5 hours until evolution of gases (particularly ammonia) has ceased. The reaction mixture is then dissolved in an excess of 10 percent by weight aqueous sodium hydroxide and the polymer reprecipitated by carbonation with an excess of carbon dioxide to a pH of about 10. The product is collected, washed thoroughly with water and dried at 100° C. for 18 hours. It is very similar in its properties to the product obtained in Example 1 above. Inherent viscosity is 0.158 in trifluoroacetic acid.

Analysis.—27.7% C.; 3.9% H.; 52.4% N.

Example 6

The procedure of Example 3 is employed using the product of Example 4, under somewhat altered conditions. One gram of the mixture is suspended in 35 ml. of monofluorotrichloromethane at -56° C. and the gas stream is gradually enriched to 67 percent by volume of fluorine and maintained at that point so that during 1.5 hours about 15 g. of fluorine are passed into the suspension. The temperature rises to -33° C. due to the exothermic reaction. The reaction mixture is worked up as before to give solid incompletely fluorinated polymer and an amorphous greasy hyperfluorinated product having an impact sensitivity of less than 8 kg. cm., an oxidizing capacity of 19.4 meq. of iodine per gram and containing about 32.9 percent by weight of fluorine on analysis.

Example 7

Fluorination of ammeline (2-hydroxy-4,6-diamino-s-triazine) is effected in a manner similar to that described in Example 1.

In a 1.5 l. copper vessel of cylindrical shape immersed in a cooling bath at -16° C. is placed a copper tray containing 1.5 grams (0.012 mole) of previously thoroughly dried ammeline, the reactor is closed, flushed with nitrogen and a stream of 5.5% by volume of fluorine is passed through the reactor at a rate of about 0.02 mole of fluorine per hour. The temperature is maintained at about -16° C. throughout 7 hours (a total of 0.13 mole F_2), the fluorine is discontinued and the cooling bath is allowed to warm to room temperature during 2 hours while the volatile products are flushed through with nitrogen and collected in a trap cooled in liquid air after removal of hydrogen fluoride by passage over solid sodium fluoride maintained at 25° C. The condensate is distilled to obtain a fraction having a vapor pressure equal or less than 40 mm. of Hg at -75° C. and greater than 25 mm. of Hg at $+25^\circ$ C. A small fraction has a higher boiling point. The main fraction is chromatographed as described hereinabove and contains bis(difluoroamino) difluoromethane, tris(difluoroamino)fluoromethane, perfluoroformamidine and perfluoroguanidine in the approximate ratio (by moles) of 10:7.5:1:3. The exact ratios of formation of these products and the total yield are rather variable even in runs which are intended to be identical since it is impracticable to control every possible variable.

Example 8

The procedure of Example 7 is repeated employing 2.5 grams (0.019 mole) of dried ammeline with the fluorine

15

stream containing 5.5% by volume of fluorine for 1.5 hours and 0.1% fluorine for 6.5 hours and maintaining the outside of the reactor at -22° to -23° C. The fraction of product boiling between -75° C. and $+25^{\circ}$ C. (at atmospheric pressure) is separated, diluted with nitrogen so that it can be handled as a gas, passed through a scrubber containing 50 ml. of 5% by weight aqueous sodium hydroxide and the gases dried with calcium sulfate (hemihydrate) and collected in a trap cooled with liquid air. Vapor phase chromatography enables the separation of $\text{CF}_2(\text{NF}_2)_2$ and $\text{CF}(\text{NF}_2)_3$ in a ratio of about 2:1.

Example 9

The procedure of Example 8 is repeated employing as the source material an intimate mixture of 1.5 grams (0.012 mole) of dried ammeline and 0.5 gram (0.012 mole) of anhydrous sodium fluoride. The outside of the reactor is maintained at -18° C. The fluorine stream is 5.5% for 1.5 hours and 9.1% by volume fluorine for a further 4.0 hours. The temperature inside the reactor is found to be about -7° to $+5^{\circ}$ C. part of which is a result of the heat of reaction. A total of 0.106 mole of fluorine is employed. The product is separated as above. The compound, $\text{CF}_2(\text{NF}_2)_2$, predominates.

Example 10

Ammeline trihydrofluoride is prepared by passing anhydrous gaseous HF over ammeline in a copper boat in a black iron tube until there is an increase in weight of 34%.

Analysis.—Calculated for: $\text{C}_3\text{N}_5\text{H}_5\text{O} \cdot 3\text{HF}$ 16.0 meq./gram F. Found: 15.3 meq./gram H $+$; 15.6 meq./gram F.

In a copper U-tube (100 ml. capacity) in an ice bath are placed 1.6 grams (0.009 mole) of the above ammeline trihydrofluoride and a stream of fluorine in nitrogen is introduced (after initially flushing with nitrogen). For two hours the stream contains 9.2% by volume fluorine and for a further two hours it contains 7.3% F_2 . The temperature in the reactor reaches 17° C. during some parts of the reaction. A total of 0.099 mole of F_2 is employed. The product is separated as above to provide a fraction from which $\text{CF}_2(\text{NF}_2)_2$ and $\text{CF}(\text{NF}_2)_3$, perfluoroformamidine and perfluoroguanidine are separated as above. The product boiling above 25° C. is obtained in almost equal amount to the total of the above.

Example 11

Ammeline trihydrofluoride (1.5 grams; 0.08 mole) is fluorinated in the apparatus and by the procedure of Example 9 cooling the reactor at -20° C. and using first 5.5% fluorine for 1.5 hours and the 9.1% fluorine for 4.8 hours. A total of 0.125 mole of F_2 is used. Products are worked up and found to contain particularly $\text{CF}_2(\text{NF}_2)_2$. It will be noted that a higher proportion of total fluorine was employed than in Example 10.

Example 12

In the apparatus of Example 10 are placed 1.7 grams (0.013 mole) of thoroughly dried ammelide (2,4-dihydroxy-6-amino-s-triazine) and, after the usual preliminary flushing with nitrogen, a stream of fluorine in nitrogen (5.2% to 7.6% by volume) is passed over the ammelide at 25° C. for 7.4 hours. The volatile products (boiling below 25 mm. at 25° C.) includes $\text{CF}_2(\text{NF}_2)_2$ and $\text{CF}(\text{NF}_2)_3$. In addition there is a considerable amount of solid amorphous product with an impact sensitivity less than 100 kg. cm. and with an oxidative capacity of 13.9 meq. of iodine per gram. Analysis shows 21.0% C; 27.1% F; 31.0% N.

Example 13

Melamine (1.20 grams; 2,4,6-triamino-s-triazine) is fluorinated in the apparatus of Example 7 after grinding to a fine powder and drying at 100° C. and 0.1 mm. Hg pressure for 16 hours. During the reaction the tempera-

16

ture (external) and concentration of fluorine are increased as shown in the following table.

5	Time, hours	Temp., $^{\circ}\text{C}.$	Percent F_2 in gas stream	Moles F_2 added	Total F_2
	1.5	-18	5.5	0.029	0.029
	2.0	-18	9.1	0.038	0.067
	1.6	-10	9.1	0.030	0.097
	.66	-6	21.6	0.055	0.152

10 The amorphous product remaining in the reactor is yellow, free-flowing and oxidizes iodide ion. The volatile components are separated as above to give fractions as follows:

15 (1) Boiling -178° C./0.1 mm. Hg to -78° C./44 mm. Hg.

(2) Boiling -78° C./44 mm. Hg to $+25^{\circ}$ C./50 mm. Hg.

(3) Boiling —above 25° C./50 mm. Hg.

20 Fraction 2 contains compounds $\text{CF}_2(\text{NF}_2)_2$ and $\text{CF}(\text{NF}_2)_3$ which are isolated by gas chromatography as described above. This fraction also contains small amounts of perfluoroformamidine and perfluoroguanidine.

25 Fraction 3 was divided by chromatography into several subfractions. One of these possessed, among others, nuclear magnetic resonance peaks at $+101\phi$ and $+87.2$ to $+83.8\phi$ which are assigned to the groupings $-\text{NCF}_2\text{NF}_2$ and $-\text{NCF}_2\text{NCF}_2-$ in the compound

30 Another subfraction showed several peaks including one at $+101\phi$, assigned to $-\text{NCF}_2\text{NF}_2$, as occurs in the compound

35 Repeating the above procedure using melamine intimately mixed with sodium fluoride and with melamine trihydrofluoride and with different concentrations of fluorine also results in the formation of volatile products from which $\text{CF}_2(\text{NF}_2)_2$ and $\text{CF}(\text{NF}_2)_3$ are isolated.

Example 14

40 The fluorination procedure described above is repeated employing 2.8 grams of dry potassium cyanelurate as the source material with 10% F_2 at 25° C. and the compounds $\text{CF}_2(\text{NF}_2)_2$, $\text{CF}(\text{NF}_2)_3$, perfluoroguanidine, perfluoroformamidine, and other materials are obtained.

Example 15

45 Guanidine hydrochloride (0.74 gram; 0.008 mole) is fluorinated in the U-tube reactor of Example 10 cooled at -270° C. using 0.062 mole of F_2 (at concentrations of 7.4% to 13.1% over two hours). The heat of reaction raises the internal temperature to 0° C. The reaction mixture is found to contain the compounds $\text{CF}_2(\text{NF}_2)_2$ and $\text{CF}(\text{NF}_2)_3$, as well as perfluoroformamidine and apparently some perfluoroguanidine.

Example 16

50 Dicyanamidazole ($\text{N}\equiv\text{C}-\text{N}=\text{C}(\text{N}_3)-\text{NH}_2$) and its hydrofluoride are likewise fluorinated (at -25° C. with 4% fluorine for 1.3 hours and at $+25^{\circ}$ C. with 10% fluorine for 1.5 hours, respectively) to produce compounds $\text{CF}_2(\text{NF}_2)_2$ and $\text{CF}(\text{NF}_2)_3$. The other products may be present as well.

Example 17

55 A mixture of 1.5 grams (0.012 mole) of dry ammeline and 75 ml. of perfluorotributylamine is placed in a 10 inch long copper tube 1 inch in diameter closed at the lower end, with a reflux condenser and takeoff at the top and with a monel metal dispersion disk connected to a 70 conduit for in-gases at the bottom. After flushing with

nitrogen, fluorine in nitrogen is bubbled through the mixture the concentration being increased from 5.7 to 53% over 15 minutes and then maintained at 53% for 90 minutes so that a total of 0.5 mole of fluorine is employed. The off-gases, after passing through a sodium fluoride tube at 25° C. are passed through a "Pyrex" trap cooled in liquid air in which the volatile products of the reaction collect. During the fluorination reaction the mixture in the tube reaches about 38° C. The condensate in the liquid air trap is fractionated as in the above examples and from the middle fraction (boiling from about 40 mm./-75° C. to 20 mm./ 25° C. it is possible to obtain perfluoroformamidine, perfluoroguanidine, bis(difluoramino)-difluoromethane and tris(difluoramino)fluoromethane.

Example 18

The apparatus of Example 17 is charged with a mixture of 1.5 g. (0.012 mole) of ammeline and 6 grams of graphite as diluent. No liquid is used and the process provides a substantially fluidized bed. The solids are maintained in suspension by a flow of 0.013 cu. ft./min. of N₂. Florine is introduced into the gas stream at 1.8% for one hour and at 6.0% for a further two hours so that a total of 0.19 mole is employed. The temperature of the mixture is maintained between -35° and -22° C. The off-gases pass through sodium fluoride at 100° C. and are condensed and finally worked up as above. Somewhat higher yields of perfluoroformamidine and perfluoroguanidine are obtained than in Example 17 above, as well as CF₂(NF₂)₂ and CF(NF₂)₃.

EXAMPLE 19

Biguanide (1.5 g., 0.015 mole) is fluorinated for 8 hours with a stream of nitrogen containing 9-14% F₂. The apparatus is held in a cooling bath at -25° C.; the heat of reaction raises the temperature to -12° C. or occasionally higher. The products are condensed out of the exit gases by cold traps. They include CF₂(NF₂)₂, CF(NF₂)₃, perfluoroformamidine, and perfluoroguanidine. Other products are also present including one which shows nuclear magnetic resonance peaks as shown in the following table:

Position of peak	Structural assignment	Approximate relative areas
-23.0 δ	-NF ₂	4
+66.4 δ	-CF ₃	3
+89.4 δ	-NF	1
+131.2 δ	-CF	1

From these positions and area ratios of the peaks it follows that the structure of the compound is:

Because of their high oxidizing capacities the hyperfluorinated products of the invention are useful in propellant compositions when combined with fuels such as lithium and boron and with an additional oxidizer such

as ammonium perchlorate to consume any carbon which is present, such as that in the hyperfluorinated oxidizer as well as in any organic binder which is used.

What is claimed is:

5 1. A fluorinated oxidant compound selected from the group of compounds having the formula:

10 wherein R is a member of the group consisting of -NF₂, -NFCF₃, -NFCF₂NF₂, -NFCF=NF, -NFCF(NF₂)₂,

15 =NF, =N-CF₃, =NCF₂NF₂, =NCF=NF and =NCF(NF₂)₂

20 radicals; Y is a linking radical of the group consisting of

25 and =C= radicals; Z is a member of the group consisting of -F, -CF₂NF₂, -CF=NF₂,

30 and -CF(NF₂)₂ radicals; n is an integer from zero to one; R is a divalent radical only when Y is a linking radical of the group consisting of =C= and

35 and n is zero when Y is =C=.

2. The compound having the formula

3. The compound having the formula

45 4. Tris(difluoramino)fluoromethane having the formula CF(NF₂)₃.

UNITED STATES PATENT OFFICE
CERTIFICATE OF CORRECTION

Patent No. 3,461,162 Dated August 12, 1969

Inventor(s) Robert J. Koshar and Donald R. Husted

It is certified that error appears in the above-identified patent and that said Letters Patent are hereby corrected as shown below:

In column 14, line 35, "exathermic" should read --exothermic--. In column 15, line 2, "0.1%" should read --9.1%--. In column 16, line 53, "-270° C." should read -- -27° C.--. In column 17, line 48, "-NF" should read -- >NF-- and in line 49, "-CF" should read -- >CF --. In column 18, lines 20-25 should also include -- =C- --.
